UNITED STATES PATENT OFFICE

JOSEPH J. STOETZEL, OF CHICAGO, ILLINOIS, ASSIGNOR TO PNEUMATIC TUBE APPLIANCE COMPANY, OF CHICAGO, ILLINOIS, A CORPORATION OF ILLINOIS.

REGULATOR FOR PNEUMATIC SERVICE SYSTEMS.

1,104,228.

Specification of Letters Patent.

Patented July 21, 1914

Application filed October 11, 1911. Serial No. 654,126.

To all whom it may concern:

Be it known that I, JOSEPH J. STOETZEL, a citizen of the United States of America, and a resident of Chicago, county of Cook, State 5 of Illinois, have invented certain new and useful Improvements in Regulators for Pneumatic Service Systems, of which the following is a specification.

The main objects of this invention are to 10 provide an improved form of regulating device for controlling the connection between a pneumatic transmission line and the source of power, whereby the line may be at all times ready for service at full power, 15 although requiring but an extremely small amount of power during intervals of disuse; to provide a device of this kind which is automatic in its operation and adapted to practically cut off the flow of air during 20 periods when no carrier is in transit and to instantly start an adequate flow when a carrier is inserted into the line; and to provide a device of this kind which is readily 25 adjustable to suit the requirements of lines of various lengths.

An illustrative embodiment of this invention is shown in the accompanying drawings, in which:—

Figure 1 is a longitudinal section of a 30 regulating device particularly designed for use in connection with a transmission line of the suction type. Fig. 2 is a diagrammatic representation showing the manner in which the regulator is connected to a looped 35 transmission line.

In the construction shown, two transit tubes 1 and 2 are arranged as in the usual looped line, so as to provide dispatch and delivery terminals at each of two stations. 40 In the drawings, the station nearest the power plant is designated A and the distant one, B. At the station A the dispatch terminal 3^a is normally open, but the delivery terminal 4^a is normally closed by a 45 flap valve. At the station B, both tubes are normally closed and connected by a branch tube 5 so that in effect both tubes form a single continuous air duct.

The exhauster or other source of power, 50 designated by 4, is connected to the line by a suction branch near the delivery terminal 4^a in the usual manner and the regulator 7 is interposed between the exhauster and the transit tube.

In the form shown in the drawings, the 55 regulator comprises an outer cylinder or casing 8 and an inner cylinder or casing 9, the latter being preferably concentric with the casing 8 and having its interior subdivided into two chambers 10 and 11 by a 60 stationary partition 12. The lower end of the casing 8 is connected by a pipe 13 to the exhauster and the upper end is connected by a pipe 14 to the transit tube near the delivery terminal 4^a.

The upper end of the cylinder 9 is open 65 and is controlled by a valve 15. The side walls of the cylinder 9 are provided with perforations 16 and 17 connecting the annular space 18 around said cylinder with 70 the chambers 11 and 10 respectively.

The valve 15 is rigidly connected by a rod 19 with a piston 20, which is slidable in the chamber 11. The clearance space 21 in the lower end of the cylinder 9 communicates 75 with the outer atmosphere through one or more passages 22.

An annular partition 23 separates the annular space 18 from the space 24 above the inner cylinder 9, and this partition 23 is slid- 80 able vertically with respect to both the outer and inner cylinders and serves for adjusting the area of the passage provided by the openings 17. There is a passage 25 through the partition 23 which serves as a 85 by-pass between the spaces 24 and 18, and this by-pass is controlled by a screw 26, by means of which the minimum flow of air is regulated.

The outer casing 8 extends a considerable 90 distance above the top of the inner cylinder 9, and has mounted therein a tubular member 27, within which is slidably mounted a loose fitting piston valve 28. This valve is carried by a sleeve 29, which is slidably 95 mounted on the valve stem 19, and by contacting with the valve 15 limits the downward movement of the valve 28. The valve 28 is normally urged upward away from the valve 15 by means of the spring 30. The 100 outer periphery of the tube 27 is covered by a layer 31 of suitable packing material, such as leather, so as to have airtight fit with the walls of the outer cylinder, along which the tube 27 may be adjusted vertically by means 105 of set screws 32 which extend through slots 33 in the casing 8. The tube 27 has a portion of its periphery cut away near the upper end

thereof, as for example, by a series of openings 34, and stop shoulders 35 are provided for limiting the upward movement of the valve 28, so that it does not move beyond a position where the maximum flow of air will pass around its edges, as indicated by the arrow 36 in Fig. 1.

The operation of the device shown is as follows:—When no carrier is in transit, the parts of the regulator occupy the positions shown by full lines in Fig. 1. When the regulator is first adjusted for the line, the ring 23 is adjusted up or down, as the case may require, to provide the proper area of passage through the openings 17 in the liner cylinder 9 to take care of the maximum rate of flow of air through the transit tube, preventing the transmission of a current. The by-pass 25 is restricted by means of the screw 30 until the flow of air is no greater than of sufficient area to cause the proper opening of the valve 15, when the free flow of air in the line is obstructed as by the insertion of a carrier into the line, as will be hereinafter explained. This adjustment determines the minimum flow of air through the transit tube, and thereby determines the amount of power which will be required to keep the system in regulation for initial operation during intervals when no carrier is in transit. This adjustment depends upon the sensitiveness of the balance of the apparatus upon the valve 15 and the stop 35. The by-pass 25 should be restricted until its area is just sufficient to promptly reduce the pressure in the chamber 21, when the line is closed by a carrier, sufficiently to allow the air pressure below the piston 20 to open the valve 15. When the valve 15 is open, it is in the position indicated by dotted lines and is far enough from the edge of the ring 23 to avoid restricting the flow of air to the chamber 10.

The main function of the valve or disk 28 is to provide means for positively closing the valve 15 at the instant that the carrier passes out of the line. This is necessary because it is desirable to have the valve 15 open so far that when it is in its open position, it will offer no obstruction to the free flow of air into the chamber 10, and will therefore not be affected by changes in the rate of flow of the air. The disk 28 is normally held in the position in which it is shown by full lines in Fig. 1 by the spring 30, which bears between the disk 28 and the valve 15. When the disk is in this position, the air may pass freely around its edges at the openings 34, and these openings are sufficiently large to take care of the maximum rate of flow of air when a carrier is in transit. As soon as the carrier passes out of the transit tube, there is a sudden increase of flow of air, and the sudden increase of air pressure above the disk 28 overcomes the force of the spring 30, and causes the disk 28 to close the valve 15.

tion of the spring, and as the least downward movement of the disk 28 causes a restriction of the flow of air around the edges of the disk by reason of the shape of the openings 34, a partial vacuum forms below the disk 28, which is then forced down by the air pressure on it until it in turn forces the valve 15 to its closed position. As soon as the valve 15 is closed, the main air flow is stopped and the air leakage around the edges of the disk increases the pressure below the disk 28 and enables the spring 30 to return the disk 28 to its normal position against the stops 35. The device is now again in readiness to operate, as before described, upon the insertion of a carrier into the line.

The sensitiveness of the disk 28 to fluctuations of the air current may be regulated by adjusting the sleeve 27 vertically and thereby adjusting the tension of the spring 30 when the valve 15 is in the uppermost position.

The lower side of the piston 20 is exposed to the free air through the passages 22, and its upper side is exposed through the openings 16 to the partial vacuum in the space 18. Similarly, the lower face of the valve 15 is exposed to the partial vacuum in the carrier 10, which communicates through the openings 17 with the chamber 18, and its upper face is exposed to the pressure of the air in the chamber 24. Under conditions of use of the system, and when the parts are in the position shown by full lines, the pressure above the valve 15 will be nearly equal to atmospheric pressure, being, however, slightly less by reason of the small flow of air through the by-pass 25. The effective area of the valve 15 is slightly greater than that of the piston 20, and this, together with the weight of the parts, insures that the forces urging the valve 15 downward are slightly greater than those tending to lift it. When a carrier is inserted into the line, it obstructs the free flow of air and the pressure in the chamber 24 will drop by reason of the flow of air through the by-pass 25, and consequently, the atmospheric pressure on the under side of the piston 20 will raise it to the upper limit of its movement and carry the valve 15 to the position indicated by dotted lines in Fig. 1, allowing the free flow of the conveying air current in the line. The maximum air flow may be regulated by shifting the ring 23 so as to vary the effective area of the openings 17. As soon as the carrier passes out of the transit tube 1, the sudden increase in the air flow causes the valve 25 to instantly fall, and the flow of air through the line is again cut down as before described.

Although but one specific embodiment of this invention is herein shown and described, it will be understood that numerous details of construction may be altered or

omitted without departing from the spirit of this invention, as defined by the following claims.

I claim:—

- 5 1. In a transmission system the combination of a transit tube, a pair of concentrically arranged casings, the outer of said casings being connected to said tube, means connected to said outer casing and adapted to cause a transmitting air current to flow through said tube and casings, a valve concentrically located with respect to said casings, and coacting with the inner of said casings, for controlling the volume of said air current through said casings, and a piston mounted in said inner casing and operatively connected to said valve, said piston being adapted to be actuated through variations in said air current for shifting said valves.
- 10 2. In a pneumatic transmission system the combination of a transit tube, a casing connected thereto, means connected to said casing and adapted to cause a transmitting air current to flow through said tube and casing, a partition located in said casing and subdividing it into two compartments, a valve adapted to be shifted for controlling communication between said compartments so as to vary the volume of said air current passing through said tube and casing, and a piston located in one of said compartments and operatively connected to said valve, said piston being adapted to be actuated by variations in said flow of air through said tube and casing, said partition having a passage leading therethrough for providing constant communication between said compartments, and means for adjusting the cross sectional area of said passage.
- 15 3. In a pneumatic transmission system the combination of a transit tube, a casing connected thereto, means connected to said casing and adapted to cause a transmitting air current to flow through said tube and casing, a partition located in said casing and subdividing it into two compartments, a valve adapted to be shifted for controlling communication between said compartments so as to vary the volume of said air current passing through said tube and casing, and a piston located in one of said compartments and operatively connected to said valve, said piston being adapted to be actuated by variations in said flow of air through said tube and casing, said partition having a passage leading therethrough for providing constant communication between said compartments.
- 20 4. In a pneumatic transmission system the combination of a cylinder having one end connected to the transit tube and having its other end connected with a source of power, a second cylinder located within the first, a partition subdividing said second cylinder into two compartments, the upper end of said cylinder being open and said cylinder having openings in its side walls connecting each of said compartments with the space around said inner cylinder, a piston mounted in the lower compartment of said cylinder, a valve controlling the open upper end of said cylinder and connected with said piston, the space in said inner cylinder below said piston being connected with the outer air, a second partition extending across the space between said cylinders and having a by-pass passage, and means above said valve and adapted through an increase in the volume of air entering said casing to close said valve.

Signed at Chicago this 9th day of October 1911.

JOSEPH J. STOETZEL.

ing, a partition located in said casing and subdividing it into two compartments, a valve adapted to be shifted for controlling communication between said compartments so as to vary the volume of said air current passing through said tube and casing, a piston located in one of said compartments and operatively connected to said valve, said piston being adapted to be actuated by variations in said flow of air through said tube and casing, said partition having a passage leading therethrough for providing constant communication between said compartments, and means for adjusting the cross sectional area of said passage.

4. In a pneumatic transmission system, the combination of a cylinder having one end connected to the transit tube and having its other end connected with a source of power, a second cylinder located within the first, a partition subdividing said second cylinder into two compartments, the upper end of said cylinder being open and said cylinder having openings in its side walls connecting each of said compartments with the space around said inner cylinder, a piston mounted in the lower compartment of said cylinder, a valve controlling the open upper end of said cylinder and connected with said piston, the space in said inner cylinder below said piston being connected with the outer air, a second partition extending across the space between said cylinders and having a by-pass passage, and means above said valve and adapted through an increase in the volume of air entering said casing to close said valve.
